(57) **CLAIM**

The ornamental design for a baby bottle tether, as shown and described.

DESCRIPTION

FIG. 1 is a top, front, left perspective view of a baby bottle tether, showing my new design;

FIG. 2 is a top, rear left perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view of the baby bottle tether of FIG. 1; and,

FIG. 8 is a bottom plan view thereof.

In the drawings, the equal-length broken lines depict unclaimed portions of the baby bottle tether and form no part of the claimed design.

1 Claim, 7 Drawing Sheets
